COMBINED BOTTLE AND SUPPORT CLIP THEREFOR

Fred J. Jacobs, Fairlawn, N.J., assignor to Knomark, Inc., Jamaica, N.Y.

Filed Aug. 30, 1972, Ser. No. 284,923

Term of patent 14 years

U.S. Cl. D9—10   Int. Cl. D9—01

FIG. 1 is an elevational view of a combined bottle and support clip therefor showing my new design;

FIG. 2 is a side elevational view with the combined bottle and support clip therefor being in an operational, inverted position and the cap being removed and the support clip being extended;

FIG. 3 is an elevational view looking from the right of FIG. 2;

FIG. 4 is a top plan view thereof;

FIG. 5 is a bottom plan view thereof; and

FIG. 6 is an elevational view looking from the left of FIG. 2.

I claim:

The ornamental design for a combined bottle and support clip therefor, as shown and described.
